(57) **CLAIM**

The ornamental design for a modular LED video screen, as shown and described.

DESCRIPTION

1. Modular LED video screen

1.1 : Perspective

1.2 : Front

1.3 : Back

1.4 : Left

1.5 : Right

1.6 : Top

1.7 : Bottom

1.8 : Perspective

1. Purpose of this design product: The present design product is used for splicing and forming LED display screens. 2. Design point of this design product: Shape of the design. 3. Picture or photograph that best embodies the design point of this design: FIG. 1.1.

1 Claim, 8 Drawing Sheets
